UNITED STATES PATENT OFFICE.

EDMOND M. POULIN, OF BOSTON, AND HOWARD F. EATON, OF QUINCY,
MASSACHUSETTS.

RAILWAY-SWITCH.

SPECIFICATION forming part of Letters Patent No. 601,382, dated March 29, 1898.

Application filed August 2, 1897. Serial No. 646,772. (No model.)

To all whom it may concern:

Be it known that we, EDMOND M. POULIN, residing in Boston, county of Suffolk, and HOWARD F. EATON, residing in Quincy, county 5 of Norfolk, State of Massachusetts, citizens of the United States, have invented a new and useful Improvement in Railway-Switches; and we do declare the following to be a full, clear, and exact description of the invention, 10 such as will enable others skilled in the art to which it pertains to make and use the same.

Our invention relates to an improvement in switches for street-railways, although the same may, if desired, be used on any system of rail- 15 ways.

The object of our invention is to provide a switch that is self-cleaning in its movement and also to provide an automatic device that will keep the tongue of the switch in such a 20 position as to cause a moving car coming onto the switch to turn to the right and allow a car coming in the opposite direction to pass by and over the switch, as upon a turnout of a single-track road. The bed of the switch is 25 made flat on its upper surface, so that the movement of the tongue acts as a brush and removes all dirt, stones, or other obstructions, thereby rendering it impossible to fill up and clog itself.

30 Figure 1 is a top or plan view of a single-track road, showing a turnout and switch in its normal position. Fig. 2 is an enlarged plan view with part of the cover of the spring-box broken away. Fig. 3 is a section on line 33. Fig. 4 is a section on line 44, Fig. 2, and looking toward the right. Fig. 5 is a section on line 55, Fig. 2, and looking toward the right. Fig. 6 is a section on line 66, Fig. 4, and shows the spring mechanism for throwing 35 the switch into its normal position.

As shown in Fig. 1, A is the switch with its accompanying frog A', and B B' are the rails of the main track, while the branch or turnout rails are designated as B² B³.

40 It will be seen that the casting of the bed of the switch A has secured upon its upper surface a flat steel plate a, upon which the wheel of the car travels, and also supports the tongue C, which is pivoted on the bed-plate a at the point a'.

It will be seen as a car approaches the switch

the wheel D is supporting the car upon its tread a². As the car continues forward on the decline a³ the flange a⁴ comes in contact with the bed a, as at the point a⁵, and thereby 55 transfers the weight of the car from the tread to the flange of the wheel without any perceptible jar. As the car proceeds forward the flange of the wheel D will come in contact with the switch C, thereby guiding it to 60 the right until the flange of the opposite wheel D' is by the point a⁶ on the branch rail B³, which now becomes the guiding-wheel and guides the wheel D, traveling on its flange, toward the incline a⁷ of the branch rail B², 65 and when the wheel D comes in contact with the incline a⁷ of the branch rail B², as shown at the point a⁸, the weight of the car is transferred back from the flange of the wheel a⁴ to its tread a², and the car is now side-tracked. 70 A car coming in the opposite direction on the rails B B' will when the flange of the forward wheel comes in contact with the tongue C force it over and in line with the continuation of the rail B. As the wheel reaches the point a⁹ on the tongue C it will travel downward 75 on its tread a² until the flange a⁴ comes in contact with the incline a³ and travel up and onward on its tread a². Immediately after the car has passed over the switch the tongue 80 will return to its normal position by means of a spring tension.

The spring-tension mechanism is inclosed in a box b, secured by suitable bolts to the under side of the bed of the switch, and has 85 an opening b' on one side and level with the street to give access to the box.

To prevent water from entering, a watertight cover b² is provided and also a loose cover b³ level with the street.

Pivoted in the box, as at b⁴, is a right-angle shaft b⁵, which extends up and through a stuffing-box b⁶ and has forming part of it an arm b⁷, as shown in Figs. 2 and 3, which engages with the tongue C, as at b⁸. The lower end 95 of the shaft b⁵ is made square-shaped, and upon that part is secured an arm b⁹, having pivoted on its outer end a plunger-arm b¹⁰, encircled by a spring b¹², fastened at the outer end b¹³ and loose at its opposite end b¹⁴, but 100 bearing against the stationary projection b¹⁵. It will thus be seen that a movement of the

tongue in the direction of the arrow 10 will compress the spring b^{12} , which is of sufficient strength to return the tongue to its normal position.

- 5 As the wheel of the car travels from the point a^3 to that at a^7 it will be readily seen that the necessity of a rail is dispensed with, thus leaving the bed open on that side, removing the chances of filling in and making the 10 switch inoperative. In its normal position it rests against the flange c , so as to provide a rigid backing for the tongue when the flange of a car-wheel strikes it before turning off on the turnout.
- 15 The tongue in its normal position is over considerably more than is actually required to guide a car onto the side track, thus obviating the possibility of a car going to the left, as would be the result in using the pointed 20 switch. The tongue being the full width throughout its length prevents the tongue from being sprung, as is often the result with narrow-pointed tongues.

It is obvious that the spring-tension device 25 could be omitted and the switch used in the ordinary manner.

We claim—

1. The combination, in a railway-switch, of a flat bed-plate, with the rails ending on the 30 bed, and having a decline on their upper surfaces, from a point commencing where they lap on the plate, to their extreme ends, and a tongue made on a decline from a point between the pivot a' to its free end, and a flange 35 made a part of the switch-bed to limit the movement of the tongue, substantially as described.

2. The combination, in a railway-switch, of a flat bed-plate, with the rails ending on the 40 bed, and having a decline on their upper surfaces from a point commencing from where

they lap on the plate to their extreme ends, and a tongue made the same width throughout, and also made on a decline from a point between the pivot a' to its free end, and a 45 flange made a part of the switch-bed to limit the movement of the tongue, substantially as described.

3. The combination, in a railway-switch, of a flat bed-plate, with the rails ending on the 50 bed, and having a decline on their upper surfaces from a point commencing from where they lap on the plate to their extreme ends, and a tongue made the same width throughout, and also made on a decline from a point 55 between the pivot a' to its free end, and a flange, made a part of the switch-bed, to limit the movement of the tongue, which is held against the flange by a right-angle shaft, pivoted in the box, and at its lower end a lever 60 connecting with a plunger encircled with a spring from which the necessary tension is obtained, substantially as described.

4. The combination, in a railway-switch, of a flat bed-plate, with the rails ending on the 65 bed, and having a decline on their upper surfaces, from a point commencing where they lap on the plate, to their extreme ends, and a tongue made on a decline, from a point between the pivot a' to its free end, and a flange 70 made a part of the switch-bed, to limit the movement of the tongue, which is held against the flange by a right-angle shaft pivoted in the box, and at its lower end is a lever connecting with a plunger encircled with a spring, 75 from which the necessary tension is obtained, substantially as described.
